DESIGN FOR A TEXTILE FABRIC

Marvin L. Spirn, Brooklyn, N. Y., assignor to The Eastern Isles Importing Co., New York, N. Y.

Application October 8, 1938, Serial No. 80,330

Term of patent 3½ years

To whom it may concern:

Be it known that I, Marvin L. Spirn, a citizen of the United States, residing at Brooklyn, in the county of Kings and State of New York, have invented a new, original, and ornamental Design for a Textile Fabric, of which the following is a specification, reference being had to the accompanying drawing, forming part thereof, wherein the figure is a plan view of a textile fabric, showing my new design.

I claim:

The ornamental design for a textile fabric, substantially as shown.

MARVIN L. SPIRN.
